UNITED STATES PATENT OFFICE.

DOMINICK CALANDRA, OF LONG ISLAND CITY, NEW YORK.

DRYING-FRAME.

1,101,995.

Specification of Letters Patent. Patented June 30, 1914.

Application filed March 4, 1914. Serial No. 822,278.

To all whom it may concern:

Be it known that I, DOMINICK CALANDRA, a citizen of the United States of America, residing at Long Island City, in the county 5 of Queens and State of New York, have invented certain new and useful Improvements in Drying-Frames, of which the following is a specification.

My invention relates generally to drying frames or supports, and has been especially devised for use in supporting trays or pans of macaroni, vermicelli and the like, in the drying room, and moving such trays in quantities into and out of the drying room.

15 In the manufacture of such articles as macaroni and vermicelli on a large scale, it is essential to economy of manufacture that large quantities of the articles be simultaneously under treatment in as small a 20 space as possible, and that after treatment the articles be so situated as to be capable of quick removal from one place to another. It is also desirable, in the interests of hygienic treatment of the macaroni and vermicelli, 25 that they come into contact with the hands of the workmen as little as possible.

It is the object of my invention to provide a drying frame or support by means of which the several desiderata above set out 30 may be satisfied.

The invention consists of the novel features hereinafter claimed, and fully described in the following specification, reference being had to the accompanying drawing, wherein—

Figure 1 is an end elevational view of my improved drying frame; Fig. 2 is a side elevational view thereof, showing in dotted lines one of the trays in position; and Fig. 3 40 is a broken horizontal sectional view on the line 3—3 of Fig. 1.

Referring by reference characters to the several figures of the drawing, 10 denotes a truck which forms the main support for the 45 drying frame. To enable the truck to be easily moved from place to place, the same is provided with the front and rear wheels or rollers 11 and the side rollers 12. Each of the rollers is supported on a pivot 13 in 50 suitable brackets 14. The front and rear rollers are at the center, approximately, of the shorter sides of the truck 10, while the side rollers 12 are at the approximate center of the longer sides of the truck 10. The 55 rollers 12 are preferably of greater diameter

than the rollers 11 in order that the truck may be easily turned.

Secured intermediate the ends of each of the shorter sides of the truck is an upright or vertical bar 15, which may be of any desired height, and is preferably braced by the inclined brace rods or bars 16 extending from the truck 10 to a point intermediate the ends of the bar 15. By the arrangement described, the uprights 15 are rigid with the truck 10. The upper ends of the uprights 15 are preferably interconnected by the cross bar 15^a.

The uprights 15 form a support for an oscillating or rocking frame, pivoted in the uprights. The rocking frame includes the series of horizontal angle-iron bars 17, each bar being centrally pivoted at 18 to one of the uprights 15. It will be understood that a series of bars 17 is pivotally carried by 70 each upright 15, that the number of bars in one series is preferably equal to the number in the other series, and that the bars in opposing series are in parallel horizontal planes. One end of each angle-iron bar 17 is also 75 preferably provided or formed integrally with a wall 17^a to form a stop for trays 19 which are adapted to be supported on the bars 17. In the drawing only certain of the bars have been shown as being provided 80 with stops 17^a, and but one tray 19 (in dotted lines) is shown in position. Each series of angle-iron bars 17 is pivotally interconnected by vertical rods 20 equidistant from the upright 15. The rods 20 cause the bars 85 17 to move in unison and to a like extent, as more fully hereinafter explained.

Pivoted to one of the braces 16 is a latch or keeper 21, designed to engage one of the angle-iron bars 17, preferably the lower bar 90 in one of the series, and this same bar may also be provided with a handle 22 by means of which the frame may be moved about its several pivots.

The operation of the invention will be 100 understood from the following description thereof: The macaroni to be dried is placed in the trays 19 and the latter are then moved into position between the opposite angle-irons 17, the front ends of the trays contacting the stops 17^a. The truck is then moved into the drying room, and when the macaroni has been dried and is to be discharged from the trays, the truck is moved 105 out of the drying room, the keeper 21 is re- 110

leased from the angle-iron bar 17 and by means of the handle 22 the entire drying frame is moved about its pivots 18 in the arc of a circle. By this motion, the front end 5 (that provided with the stop 17^a) of each angle-iron bar 17 is depressed and the macaroni falls out of the pans 19 by gravity. The angle-iron bars may then be moved in the arc of a circle in the opposite direction to 10 remove the emptied trays and make room for the filled ones. When the filled pans have been placed in position the frame is again swung into upright position, the latch 21 is replaced, and the device may be 15 wheeled into the drying room.

What I claim is:—

1. In a drying frame in combination, a pair of oppositely disposed uprights, and a series of angle bars centrally pivoted to each 20 of said uprights, the angle bars opposite each other being in parallel planes.
2. In a drying frame in combination, a pair of oppositely disposed uprights, and a series of angle bars centrally pivoted to

each of said uprights, each of said angle bars having a stop at one end thereof.

3. In a drying frame in combination, a pair of oppositely disposed vertically extending rods, a series of angle bars pivoted centrally to each of said rods, said bars being normally in a position at right angles to 30 said rods, and additional rods pivotally interconnecting said bars at each side of said first mentioned rods.

4. In a drying frame in combination, a 35 wheeled truck, and a drying frame thereon comprising oppositely disposed vertical uprights, angle bars pivoted centrally to each upright, lateral rods pivotally interconnecting the bars at each side of the upright, and 40 a latch for retaining said bars in a horizontal position.

In testimony whereof I have affixed my signature in presence of two witnesses.

DOMINICK CALANDRA.
